UNITED STATES PATENT OFFICE.

JOHN RUDDIMAN, OF HASTINGS-UPON-HUDSON, NEW YORK.

GAS-CLEANER.

1,254,438.

Specification of Letters Patent. Patented Jan. 22, 1918.

Application filed April 25, 1917. Serial No. 164,424.

To all whom it may concern:

Be it known that I, JOHN RUDDIMAN, a citizen of the United States of America, and residing at Hastings-upon-Hudson, in the 5 county of Westchester and State of New York, have invented a certain new and useful Improvement in Gas-Cleaners, of which the following is a specification.

This invention relates to gas cleaners and 10 particularly to gas cleaners for use in connection with blast furnace gases. The object of my invention is to provide an improved gas cleaner of such construction that the gas is brought into contact with a series 15 of wetted surfaces or alternatively both subjected to the action of a spray shower and also brought into contact with wetted surfaces, to secure the conjoint action of both operations combined.

20 Referring to the accompanying drawings, Figure 1 is an end elevation of a gas cleaner in which my invention is embodied in one form;

Fig. 2 is a cross section on the line 2—2, 25 Fig. 1; and

Fig. 3 is a cross section on the line 3—3, Fig. 2.

In the form here shown the apparatus is mounted upon a support 10 and comprises a 30 rectangular tank 11 having a hopper bottom 12 for holding the wash water and a semi-circular cover 13 which incloses a gas chamber 14 to which opens the gas inlet pipe 15 at one end and the gas outlet pipe 35 16 at the opposite end. Passing longitudinally through the tank 11 is a shaft 17 supported and driven from without the tank by any suitable means (not shown). Stuffing boxes 18 are provided to prevent the 40 escape of gas at the points at which the shaft pierces the wall of the tank. Upon the rectangular mid-portion of the shaft within the tank, is arranged a series of circular perforated baffle plates 19 and 20.

45 Nozzles 21 are fitted into the holes of each baffle plate, except the last of the series, the sum of the area of the nozzles in each baffle being slightly in excess of twice the area of the gas inlet pipe 15. The baffle plates are 50 suitably spaced apart along the shaft and supported in a vertical position and parallel to each other by ferrules 22 on the shaft and by ferrules 23 on the bolts 24 which pass through the series of baffles at a convenient radial distance from the shaft and bind the baffles together when the nuts 55 25

are set up. Collars 26 at each end of the baffle series are secured upon the shaft by set screws and maintain the same in predetermined position upon the shaft. Alternatively the baffles may be secured to the shaft by flanges bolted to each baffle and having hubs, with set screws, which serve to space the baffles apart. This construction would be employed preferably in gas cleaners of large size.

In any event, the baffles 19 and 20 have their nozzles 21 so arranged that those of the baffles 19 discharge against the blank interspaces between the nozzles 21 on the baffles 20, and vice versa, so that the gas issuing from the nozzles in fairly close proximity to the adjacent baffles is brought into intimate contact with the blank spaces of the latter. There is consequently little or no chance for solid particles in the gas 75 to be carried through the cleaner without coming in contact with the wetted surface of some one or other of the successive baffles.

80 While the arrangement of the perforations in the baffle plates may be variously modified, I prefer that shown, viz., with the holes arranged in parallel lines at right angles to each other, since by this arrangement I secure the greatest number of apertures and the least weakening of the baffle plate in proportion to its capacity. I am aware that in prior art cleaners of this general type the apertures in the baffle plates have been 85 arranged in staggered relation to each other but as far as I have been able to discover the practice has heretofore been to arrange the apertures in radial lines with the result that they afford less passageway for a given 90 diameter of baffle plate, and the apertures overlap toward the central portion of the plates.

95 Arranged between the baffles are spray pipes 27, while at the inlet and outlet ends 100 of the gas chamber 14 are spray pipes 28. The latter are designed to throw a spray upon the walls of the gas chamber to clean the latter, while the pipes 27 between the baffles are so arranged and with their perforations at such an angle that their jets are discharged not only against the adjacent faces of juxtaposed baffles but also into the nozzles thereof, so that both the surfaces of the baffles and the interior of the nozzles are 110 cleaned. The spray pipes are all connected to a manifold 29 which has a main control

valve 30, while each spray pipe is provided with an independent control valve 31, so that some or all of the spray pipes may be utilized as may be deemed necessary.

5 At the ends of the tank 11, I provide overflow troughs 32 which maintain the normal level of the water in the tank slightly below the center line of the shaft. A water seal is provided by the outlet pipe 33 connected 10 with the overflow trough 32 and maintains the water level in the latter lower than that of the water in the tank 11.

In the operation of blast furnaces large 15 quantities of solid materials are discharged with the gas. The coarser portion of this material is deposited in a large chamber known as a dust-catcher, and the finer particles pass on with the gas to the stoves and boilers if not arrested and removed. For 20 this purpose many types of gas cleaners are employed, with more or less success, to remove the dirt, but at considerable expense to keep the cleaners clean and also by reason of the consumption of large quantities of 25 water. I minimize the expense of the cleaning operation by combining the principle of the contact type of cleaner with the scrubber type in such manner that I can provide either cool or hot gas at will in an 30 apparatus that is practically self-cleaning and economical in the use of water. The gas coming from the dust-catcher at its initial temperature and velocity enters the gas chamber 14 where its volume is broken up 35 into a large number of jets by its passage through the nozzles 21. A portion of the dust is deposited on the wet surface of the first baffle. Passing through the nozzles of the first baffle the gas jets impinge on the 40 wet blank surfaces of the second baffle which surfaces are directly opposite the nozzles. The velocity of the gas passing through the nozzles is substantially undiminished, since the sum of the areas of the nozzles above the 45 water level is substantially equal to that of the inlet pipe or slightly greater than the latter. Dust is deposited on each baffle in succession in this way, the process being repeated as many times as desired and being 50 determined by the number of baffle plates used. The degree of conservation of the temperature of the gas governs in this type of cleaning. If it is desired to cool the gas sufficiently to use it in internal combustion 55 engines, the spray pipes between the baffles will be brought into play to furnish cooling water in finely divided form, thereby further increasing the efficiency of the cleaner by scrubbing the gases as they pass between the baffles. If desired, it is possible to 60 maintain the baffles quiescent and simply subject the gas to the action of the sprays, as it passes in its tortuous course through the baffle chamber. The dust deposited 65 upon the baffles is constantly removed by

their rotary passage through the water in the tank, so that they constantly present a freshly washed surface for the gas to impinge against and the baffles are kept cool and wet during their transit through the gas 70 chamber, the nozzles having a bucket-like effect in lifting the water into the gas chamber, thus conserving the supply on the surface of the baffle, while aiding in cleaning the gas as well as the surfaces of the baffle 75 plates. The water in the tank is constantly agitated by the passage of the baffles therethrough and this prevents the accumulation of floating dirt at the water level which might tend to adhere to the baffle plates and 80 prevent their efficient operation. The water is admitted to the tank through a main 34 which enters the tank below the water level therein. The main 34 is open to the tank only when the spray pipes are not in use or 85 should the tank be emptied by a mud-flushing operation during the use of the spray pipes. The scum which form in the trough is carried off with the overflow by the outlet pipe 33. 90

Various modifications in detail of construction will readily occur to those skilled in the art without departing from what I claim as my invention.

I claim:—

1. In a gas cleaner, a chamber having means for maintaining a supply of wash water in the lower portion thereof, a gas inlet and a gas outlet for the chamber, a pair of rotary perforated baffles dipping 100 into the wash water and interposed between the gas inlet and gas outlet, the baffle adjacent the gas inlet having nozzles projecting from its perforations and serving to direct the gas passing therethrough against 105 the interspaces between the perforations of the adjacent baffle.

2. In a gas cleaner, a chamber having means for maintaining a supply of wash water in the lower portion thereof, a gas 110 inlet and a gas outlet for the chamber, a pair of rotary baffles dipping into the wash water and interposed between the gas inlet and gas outlet, said baffles having staggered perforations and the baffles adjacent the gas inlet having nozzles projecting 115 from its perforations and serving to direct the gas passing therethrough against the interspaces between the perforations of the adjacent baffle.

3. In a gas cleaner, a chamber having means for maintaining a supply of wash water in the lower portion thereof, a gas inlet and a gas outlet for the chamber, a pair of rotary perforated baffles dipping 125 into the wash water and interposed between the gas inlet and gas outlet, the baffle adjacent the gas inlet having nozzles projecting from its perforations and serving to direct the gas passing therethrough against 130

the interspaces between the perforations of the adjacent baffle, together with spray pipes between the baffles.

4. In a gas cleaner, a chamber having means for maintaining a supply of wash water in the lower portion thereof, a gas inlet and a gas outlet for the chamber, a pair of rotary perforated baffles dipping into the wash water and interposed between the gas inlet and gas outlet, the baffle adjacent to the gas inlet having nozzles projecting from its perforations and serving to direct the gas passing therethrough against the interspaces between the perforations of the adjacent baffle, together with spray pipes between the baffles and having their spray jets directed toward both baffles.
5. In a gas cleaner, a chamber having means for maintaining a supply of wash water in the lower portion thereof, a gas inlet and a gas outlet for the chamber, a pair of rotary perforated baffles dipping into the wash water and interposed between the gas inlet and gas outlet, the baffle adjacent to the gas inlet having nozzles projecting from its perforations and serving to direct the gas passing therethrough against the in-

terspaces between the perforations of the adjacent baffle, together with spray pipes between the baffles and means independent of the spray pipes for supplying wash water to the tank.

6. In a gas cleaner of the type specified in claim 1, the arrangement of the perforations in each baffle plate in lines at right angles to each other, to secure the greatest possible passage area in a plate of given diameter.

7. In a gas cleaner, a chamber having means for maintaining a supply of wash water in the lower portion thereof, a gas inlet and a gas outlet for the chamber, rotary perforated baffles dipping into the wash water and interposed between the gas inlet and gas outlet, and bucket-like means projecting from the faces of the baffles for lifting the wash water from the lower portion of the tank and discharging it over that face of the baffles against which the gas impinges during its passage through the chamber.

In testimony whereof I have signed my name to this specification.

JOHN RUDDIMAN.
